UNITED STATES PATENT OFFICE

2,343,044

RACK REPAIRING MECHANISM

William F. Brügmann, Evanston, Ill.

Original application April 25, 1936, Serial No. 76,454. Divided and this application July 11, 1940, Serial No. 345,017

9 Claims. (Cl. 77—62)

This invention relates in general to printing plate mounting devices, such as those employing the type of rack adapted to be secured in grooves therein disclosed in my co-pending application Serial No. 76,454, filed April 25, 1936, and issued August 6, 1940, as United States Letters Patent No. 2,210,749, and it relates more particularly to the apparatus for repairing such racks. The present application is a division of said Patent No. 2,210,749.

While the instant invention is clearly applicable to printing press plate cylinders and to plate supporting bases for flat bed presses, it is shown and described herein in conjunction with the former, since its advantages in such an installation are more readily apparent.

The prior art discloses the cutting of helical grooves in the circumferential surface of printing press cylinders within which register hooks are adapted to be mounted, and the provision of a rack or racks therein with which driving means, such as gears or worms, in the hooks may cooperate to move the hooks longitudinally of the grooves into and out of clamping engagement with the usual printing plates. These prior art racks, however, and the methods employed in mounting them in the grooves in the cylinders have certain practical disadvantages which it is the purpose of the instant invention to overcome.

Heretofore the racks have been pushed or pulled longitudinally into T-slots cut adjacent the bottom of the grooves. Since the racks are subjected to great strain by the driving elements of the hooks both in their initial registering movements, and during a run by the action of the impression cylinders on the printing plates, undue wear of certain portions of the racks and breakage of some of the teeth thereof naturally follow in the course of time. In the prior art devices it is then necessary to remove the entire rack from the full length of the groove, even though but a small portion thereof has been damaged. To do this, the plate cylinder must be taken out of the press and shipped to the factory where the necessary tools and equipment are available to do the work, and, in the meantime, the press is completely out of commission.

The parent case, of which this application is a division, discloses a novel rack and method and apparatus for inserting the same in a groove in a printing plate cylinder, from the top of the groove, and riveting it in the bottom portion thereof. This novel rack is designed to eliminate the above described disadvantages in repairing any desired portions thereof, and the instant ap-

plication deals more particularly with such repairing.

A principal object of the invention is the provision of novel apparatus for repairing any desired portion of such a rack without necessitating the removal from the press of the plate supporting member in which the rack is mounted.

Another important object of the invention is the provision of means for repairing the damaged portion or portions of such a rack by removing such damaged portions only and replacing them with new pieces of rack of the same size.

Numerous other objects and advantages of the invention will be apparent as it is better understood from the following description, which, when taken in connection with the accompanying drawing, discloses a preferred embodiment thereof.

In the drawing,

Figure 1 is a top plan view of a repair drill jig mounted in operative position in a groove of a printing plate cylinder;

Figure 2 is a vertical sectional view taken substantially on the line 2—2 of Fig. 1;

Figure 3 is a vertical section taken substantially on the line 3—3 of Fig. 1;

Figure 4 is a top plan view of a trimming tool mounted in a groove of the cylinder;

Figures 5 and 6 are vertical sectional views taken substantially on the lines 5—5 and 6—6, respectively, of Fig. 4;

Figure 7 is a front elevational view of a repair riveting tool;

Figure 8 is a bottom plan view of the tool of Fig. 7; and

Figure 9 is a top plan view of a repair piece for the rack.

Referring more particularly to Figs. 1 to 6 of the drawing, portions of a printing press plate supporting cylinder 21 of well-known construction are disclosed which is provided in the usual manner with a plurality of spaced, parallel, helical grooves 23 cut in the circumferential surface thereof. The cylinder 21 is the same as that more fully illustrated in the parent application hereinbefore referred to. The grooves 23 are constructed to receive any suitable form of plate holding devices, such as the printer's register hook disclosed in my prior United States Letters Patent No. 2,124,728, issued July 26, 1938, and are provided on each side adjacent the top with longitudinal, under-cut recesses 24 within which the locking elements of the plate holding devices (not shown) are adapted to be positioned. At their lower ends, the side walls of the grooves 23 are cut back or outwardly at a slight angle and

for a short distance at 25 to provide a slightly laterally enlarged recess at the bottom of the grooves within which are mounted racks 26 adapted to be engaged by the driving gears of the printer's register hooks.

The racks 26 are provided with teeth 27 on their upper surfaces formed integrally therewith, and with longitudinal, marginal recesses 28 on either side of and extending slightly below the root line or bottom portion of the teeth 27. The parent Patent No. 2,210,749 discloses means for inserting a rack 26 into a groove 23 from the top thereof and rigidly securing the rack in the bottom of the groove by displacing parts of the marginal portions of the rack laterally into the inclined recesses 28 at the bottom of the groove. When the racks 26 are secured in place in the bottom of the grooves 23, the marginal recesses 28 form gutters along the sides of the teeth 27 for the accumulation and drainage of foreign matter, as well as facilitating the securing of the racks within the grooves 23. The racks 26 are also preferably provided with a substantially centrally located, longitudinal recess or groove 29 in the bottom surface thereof for a purpose which will be explained hereinafter.

It is of course necessary in inserting the racks as described in the parent case, to remove the printing plate supporting cylinder from the press. After the cylinder has been mounted in the press, however, the racks 26 may be repaired by use of the mechanism shown herein without removing the cylinder therefrom.

Referring more particularly to Figs. 1, 2 and 3, a drilling jig 82 is shown which is substantially rectangular in shape, with the lower portion thereof adapted to fit slidably into a groove 23 in the plate supporting member 21. The jig 82 is provided with an upper marginal flange 83, which rests upon the top surface of the plate supporting member 21 when the jig is positioned in a groove 23. The bottom surface of the jig 82 is provided with a plurality of teeth 84, which are adapted to engage between the teeth 27 of the rack 26 in the bottom of the groove 23. Adjacent each end, the lower portion of the jig 82 is provided with a recess 85, which communicates at its upper end with a vertical bore 86. A clamping bolt 87 is mounted in each of the bores 86, and is provided at its lower end with an elongated head portion 88 disposed within the recess 85. The upper end of each of the clamping bolts 87 is threaded for engagement by a nut 89, and is provided with an angular, axially disposed recess or bore 91 (Fig. 1). The center portion of the jig 82 is provided with a plurality of longitudinally spaced bores or apertures 92 and a similar aperture 92' at one end thereof, the vertical axes of all of which apertures coincide with the longitudinal axis of the jig. Two additional bores or apertures 93 are provided adjacent the end aperture 92 furthest from aperture 92', which are spaced to either side thereof and have their center lines disposed on a cross line at the same angle as the teeth 84 and 27.

When it is desired to repair a particular portion of one of the racks 26, the drilling jig 82 is inserted into the groove 23 over that portion of the rack which is to be repaired. The teeth 84 of the jig insure its being properly positioned relative to the teeth 27 of the rack 26. A key or tool (not shown) is inserted in the angular recesses 91 to turn the clamping bolts 87. A partial rotation of the clamping bolts 87 will turn the elongated head portions 88 thereof into en-

gagement with the undercut recesses 24 in the groove 23. The nuts 89 are then tightened to bring the head portions 88 upwardly into firm locking contact with the top walls of the recesses 24 and force the teeth 84 downwardly into the spaces between the teeth 27 of the rack.

The apertures or bores 92, 92' and 93 are all used as guides for a drill of any suitable construction. The drill will cut downwardly through the rack 26, with the groove 29 in the bottom portion thereof insuring that the rack is completely cut through without damaging the lower surface of the groove 23. It is preferred that a bottoming drill be employed, and a suitable stop collar may be set thereon to limit downward movement of the drill by contacting the upper surfaces of the jig 82. This operation having been performed, the jig 82 is removed from the groove and reversed end for end and replaced in contact with the same portion of the rack that it engaged in its first position. The same drilling operation, using all of the apertures 92, 92' and 93, is then repeated.

The apertures 92 and 92' are spaced so that the center lines of adjacent apertures are a distance apart slightly less than twice their diameters. Consequently, these two drilling operations will result in eight overlapping holes being cut through the center of the rack, as determined by apertures 92 and 92', to completely cut away the center portion of that part of the rack 26 which is being repaired. The jig 82 will be so placed in its reversal between drilling operations, that the hole that is cut through the rack as determined by the end aperture 92' will have its center line on the same line as the holes determined by the guide apertures 93 in the reverse position of the jig 82, because the transverse center line of apertures 93 is spaced from that of aperture 92 adjacent thereto a distance slightly less than the diameters of these apertures. The end portions of that part of the rack 26 being cut out will thus be cut away as shown at 94 in Fig. 4.

A trimming jig, indicated generally by reference numeral 95, is then employed to square off the jagged end portions 94, of that part of the rack 26 remaining in the groove 23. Referring more particularly to Figs. 4 to 6, the trimming jig 95 is rectangular in shape and of such a size as to fit loosely within the groove 23. The jig 95 is provided with an upper marginal flange 96, which is adapted to rest upon the top surface of the plate supporting member 21 when the jig is positioned in the groove 23. The bottom surface of the jig 95 is provided with a plurality of teeth 97, which are adapted to engage between the teeth 27 of the rack 26 on one side or the other of that portion of the rack which has been cut away in the drilling operation.

The jig 95 is provided with a recess 98 in its lower portion which communicates with a vertical bore 99 having a clamping bolt 101 extended therethrough. The bolt 101 is provided with an elongated head portion 102 at its lower end, and is threaded adjacent its upper end for engagement with a locking nut 103. An angular recess or bore 104 extends downwardly into the upper end of the clamping bolt 101. The members 101, 102 and 103 are substantially identical, both in form and function, to the members 87, 88 and 89 of the drilling jig 82.

One of the lower corners of the trimming jig 95 is cut away at 105 (Fig. 6) and a vertical bore extends through the jig adjacent the rear end of this cut-away portion. The lower end of the

bore 106 is enlarged to provide an angular chamber within which is slidably positioned the lower rectangular head portion of a chisel or cutting member 107, which terminates at its lower end in a blade 108. The upper end of the chisel 107 is threaded and extends above the top surface of the jig 95. A bolt 109 is screwed on the upper end of the chisel 107 to limit the downward movement thereof, and is held in set position by a locking nut 111.

The trimming jig 95 is positioned in the groove 23 in the same manner as the drilling jig 82. The teeth 97 insure proper longitudinal positioning of the jig, so that the blade 108 of the chisel 107 will be directly above the side surface of the last remaining tooth 27 of the rack 26 adjacent the cut-away portion thereof. Since the blade 108 of the chisel is disposed at the same angle as the teeth 97 and 27, a sharp blow imparted to the chisel will cleanly trim off the jagged edges 84 of the rack that are left by the drilling operation.

If it is desired, two chisels or cutters 107 may be mounted, one in either end, in the trimming jig 95, rather than the one herein disclosed.

Any loose pieces or chips that are left in the bottom of the groove 23 after the drilling and trimming operations have been performed, may be blown out of the groove or removed therefrom with a magnet.

A repair piece 112 (Fig. 9), shaped to fit exactly in the blank space in the rack 26 resulting from the above drilling and trimming operations, is inserted into this space in the bottom of the groove 23, and riveted in place with a hand riveting tool, such as that disclosed in Figs. 7 and 8 and indicated by reference numeral 113.

The tool 113 is substantially square in cross section, and is cut away at its bottom end to provide a transverse recess 114. Depending from the bottom of the tool on either side of the recess 114 are longitudinally disposed teeth 115. The teeth 115 have a vertical cross-sectional shape similar to the teeth 18 of the riveting roller 14 of the parent case. The recess 114 is of substantially the same width as the tooth 27 of the rack, so that the tool 113 may be disposed in the slot 23 with the teeth 115 straddling the central portion of the repair piece 112. Downward pressure on the tool 113 will spread some of the metal of the marginal edges of the repair piece into the angular recesses 25 at the bottom of the groove to rivet the repair piece in place.

With the above described mechanism, the racks 26 or any desired portions thereof may be readily repaired without the necessity of removing the plate cylinder 21 from the press. The longitudinal groove 29 in the bottom surface of the rack 26 acts as a clearance for the drill in cutting through the rack. The same result could be obtained by cutting a recess in the bottom surface of the groove 23. The above described arrangement, however, is obviously much more desirable.

Should it be necessary to put in a much longer repair piece than that shown in Fig. 9, it would perhaps be easier to cut off the ends of the piece in the manner above described, and then cut through it longitudinally with a saw or narrow milling cutter operating in a suitable fixture. Regardless of the method employed, the longitudinal cutting through of the rack 26 permits it to be readily pulled out from under the angular recesses 25 in the groove 23. These recesses 25 need not be very deeply cut into the sides of the

groove, a few thousandths of an inch being sufficient to rigidly secure the rack in the bottom of the groove.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A tool guiding device for repairing racks mounted in grooves in a printing plate supporting member, comprising a body portion adapted to be positioned in a said groove and having an extension from one surface thereof adapted to engage between the teeth of the rack in said groove, said body portion also having tool guiding means associated therewith, and means for securing said body portion in selected position in said groove so that said tool guiding means is disposed in a desired relationship to the teeth of said rack.
2. A drilling jig, comprising a body portion adapted to be positioned in a groove in a printing plate supporting member and having drill guiding bores extending therethrough, teeth on the lower surface of said body portion adapted to mesh with a rack in said groove, and means mounted in said body portion for securing said jig in selected position in said groove.
3. A trimming tool, comprising a body portion adapted to be positioned in a groove in a printing plate supporting member, teeth on the bottom surface of said body portion adapted to mesh with a rack in said groove, a cutter slidably mounted in said body portion, and means mounted in said body portion for securing said tool in selected position in said groove.
4. A tool guiding device for repairing a toothed rack secured in the undercut bottom portion of a groove having recesses in the side walls thereof, comprising a body portion positionable in said groove and having teeth on the bottom surface thereof adapted to mesh with the teeth of said rack to properly position the device longitudinally of the groove, said body portion also having tool guiding means associated therewith, and means mounted in said body portion and adjustable relative thereto for engaging the recesses in the side walls of the groove to prevent vertical displacement of the device therefrom so that said tool guiding means is disposed in a desired relationship to the teeth of said rack.
5. A drilling jig, comprising a body portion positionable in a groove having a toothed rack secured therein, means for removably securing said body portion in said groove, apertures spaced from each other longitudinally of said body portion slightly less than twice each of their diameters, other apertures having the same diameter disposed to either side of an end one of said longitudinally spaced apertures and formed on a transverse axis spaced slightly less than said diameter beyond a parallel transverse axis passing through said end aperture, said apertures extending through said body portion for guiding a drill, and teeth formed on said body portion to mesh with the teeth of said rack, said teeth and said apertures being so positioned relative to each other as to enable end for end reversal of said body portion in said groove to place the center of each aperture slightly less than the diameter

thereof from its original position longitudinally of said groove.

6. A trimming tool, comprising a body portion positionable in a groove having a toothed rack secured therein, means for removably securing said body portion in said groove, a cutter slidably mounted in said body portion, and teeth formed on said body portion to mesh with the teeth of said rack, said teeth and said cutter being so positioned relative to each other as to bring the latter substantially in the plane of the side surface of one of the teeth of the rack.

7. A tool guiding device for repairing a toothed rack mounted in a groove, comprising a body portion positionable in said groove and having means adapted to engage the teeth of said rack to properly position the device relative to a selected portion of said rack, said body portion also having tool guiding means associated therewith, and locking means mounted in said body portion and operable to engage said groove to prevent displacement of the device relative to said rack

so that said tool guiding means is disposed in a desired relationship to the teeth of said rack.

8. A drilling jig, comprising a body portion positionable in a groove having a toothed rack mounted therein, said body portion having a drill guiding bore extending therethrough, means adapted to engage the teeth of said rack to properly position said bore relative thereto, and locking means operable to engage said groove to prevent displacement of the tool relative to said rack.

9. A jig for use in repairing a toothed rack mounted in a groove, comprising a body portion with tool guiding means and having means for engaging the teeth of said rack to properly position the jig relative to a selected portion of the rack, and means for locking said jig in selected position in the groove so that said tool guiding means is disposed in a desired relationship to the teeth of the selected portion of the rack.

WILLIAM F. BRÜGMANN.
